CLAIM

I claim the ornamental design for a green roof module, as shown.

DESCRIPTION

FIG. 1 is a top perspective view of the green roof module according to the invention;

FIG. 2 is a bottom perspective view of the green roof module according to the invention;

FIG. 3 is a top elevation view of the green roof module according to the invention;

FIG. 4 is a back elevation view of the green roof module according to the invention;

FIG. 5 is a front elevation view of the green roof module according to the invention;

FIG. 6 is a left side elevation view of the green roof module according to the invention; and,

FIG. 7 is a right side elevation view of the green roof module according to the invention.
